UNITED STATES PATENT OFFICE.

WILLIAM ALAXANDER SPARKS AND JAMES EP COLLINS, OF MOUNT VERNON, WASHINGTON, ASSIGNORS OF ONE-HALF TO GEORGE M. SINCLAIR AND THOMAS SMITH, OF SAME PLACE.

CAR-COUPING.

SPECIFICATION forming part of Letters Patent No. 544,598, dated August 13, 1895.

Application filed September 24, 1894. Serial No. 523,966. (No model.)

To all whom it may concern:

Be it known that we, WILLIAM ALAXANDER SPARKS and JAMES EP COLLINS, citizens of the United States, residing at Mount Vernon, 5 in the county of Skagit and State of Washington, have invented a new and useful Car-Coupling, of which the following is a specification.

The invention relates to improvements in 10 car-couplings.

The object of the present invention is to improve the construction of pin-and-link car-couplings, and to provide one capable of coupling automatically and adapted to convey the 15 link of an approaching or opposite draw-head into the mouth of its draw-head to avoid guiding the link by hand and to obviate the necessity of going between cars during coupling.

The invention consists in the construction 20 and novel combination and arrangement of parts hereinafter more fully described, illustrated in the accompanying drawings, and pointed out in the claim hereto appended.

In the drawings, Figure 1 is a perspective 25 view of a car-coupling constructed in accordance with this invention and shown set for automatic coupling. Fig. 2 is a longitudinal sectional view of the same. Fig. 3 is a similar view showing the position of the parts 30 when coupled. Fig. 4 is a detail perspective view of the link guider and conveyer.

Like numerals of reference indicate like parts in all the figures of the drawings.

1 designates a draw-head of ordinary 35 configuration, provided with a longitudinal link-opening 2, and having at the top of the same a longitudinal way 3, formed by opposite grooves and receiving a horizontally-disposed longitudinally-movable slide 4, adapted to 40 support a coupling-pin 5 in an elevated position preparatory to coupling. The coupling-pin 5 is elliptical in cross-section, and the coupling-pin perforation 6 of the draw-head is of similar shape to prevent the coupling-pin 45 from turning. The slide is provided with a corresponding coupling-pin perforation 7, having a beveled rear portion and adapted to

register, when the slide is moved inward, with the coupling-pin perforation of the draw-head to cause the coupling-pin to fall and engage a link 8.

The front end of the slide is provided with a head or buffer 9, adapted to be engaged by the draw-head of an approaching or opposite car to move the slide inward as the cars come 55 together, and the upper portion of the front of the draw-head is provided with a recess 10, conforming to the configuration of the head or buffer, to receive the same and to permit the buffer, which extends upward from the 60 slide, to lie flush with the outer face of the draw-head. The movement of the slide is limited by a removable pin 11, located at the back of the draw-head, in a suitable perforation thereof, and engaging or fitting in a longitudinal slot of the rear portion of the slide.

The link of an opposite draw-head, when cars come together for coupling, is received and conveyed into the mouth of the draw-head 1 by a link-guider 13, which is hinged 70 to the slide at a point intermediate of the ends thereof and at the lower face of the same, and which, when the slide is extended, as illustrated in Fig. 1 of the accompanying drawings, has its front portion 14 resting 75 against and supported by the front of the draw-head. The link guider and conveyer has its front portion 14 shovel-shaped, the sides 15 being slightly curved upward to retain the link on it, and it is provided in rear of the 80 shovel portion with a curved neck or shank 16, extending upward and terminating in an open eye 17, which is hinged between depending perforated ears or flanges 18 of the slide; or by any other suitable construction 85 it may be connected hingedly to the lower face of the slide. The open eye detachably connects the link-guider to the slide, and in event of the breakage of either of the parts they may be readily disconnected and detached from the draw-head to permit a new 90 part to be supplied. When the slide is withdrawn into the draw-head, the link-guider is arranged within the same entirely, and it

conforms to the configuration of the bottom of the draw-head and is provided with a coupling-pin perforation 19 to permit the coupling-pin to pass through it and enter the lower portion of the coupling-pin perforation of the draw-head. The link-guider is provided, in advance of the coupling-pin perforation, with a nipple or shoulder 20, formed by upsetting the metal of the link-guider and presenting a beveled front portion and a shouldered rear portion, and forming a catch to be engaged by a link in leaving the draw-head, whereby in uncoupling the parts will be automatically set for coupling.

15 It will be seen that the car-coupling is simple and comparatively inexpensive in construction, that it possesses great strength and durability, as the movable parts do not interfere with the construction of the draw-head or materially weaken the same, and that in operation it is positive and reliable. It will also be apparent that in event of the breakage of the slide or the link-guider those parts may be readily removed by withdrawing the 25 pin 11, in order that other parts may be readily substituted.

Changes in the form, proportion, and the minor details of construction may be resorted to without departing from the principle or

sacrificing any of the advantages of this invention.

What we claim is—

In a car coupling, the combination of a draw-head having a longitudinal link-opening and provided at its front face with a recess and 35 having a longitudinal way, a slide mounted in the way and provided with a coupling-pin perforation and having at its outer end an upward extending portion conforming to the configuration of said recess and adapted to 40 fit therein, and a link-guider hinged to the lower face of the slide and composed of a curved neck or shank, and a front portion conforming to the configuration of the bottom of the draw-head and having side flanges 45 and provided with a coupling-pin perforation, and having in advance of the coupling-pin perforation a struck-up portion forming a catch, substantially as described.

In testimony that we claim the foregoing as 50 our own we have hereto affixed our signatures in the presence of two witnesses.

WILLIAM ALAXANDER SPARKS.
JAMES EP. COLLINS.
